UNITED STATES PATENT OFFICE.

MILTON B. REACH, OF SPRINGFIELD, MASSACHUSETTS, ASSIGNOR, BY DIRECT AND MESNE ASSIGNMENTS, TO R. P. K. SPECIALTY COMPANY, A CORPORATION OF NEW YORK.

SHOE-FORM.

No. 927,280.

Specification of Letters Patent.

Patented July 6, 1909.

Application filed October 29, 1908. Serial No. 460,678.

To all whom it may concern:

Be it known that I, MILTON B. REACH, citizen of the United States, residing at Springfield, Massachusetts, have invented 5 certain new and useful Improvements in Shoe-Forms, of which the following is a specification.

It is the object of my invention to provide a form for restoring the shape of boots or 10 shoes by inserting the same therein, so as to exert pressure on the interior parts for reshaping the shoe, my construction being devised for the purpose of providing a simple, inexpensive and durable form which may be 15 readily applied and which will be effective in use.

In carrying out my invention, I aim to construct the shoe form of one piece of sheet metal, which is formed to the desired shape, 20 so that all of the interior parts of the shoe may be reshaped where this is necessary, that is to say, the necessary parts of the upper and the necessary parts of the sole portion of the shoe will be subjected to the reshaping effect by the use of my improved 25 form. So far as I am aware, I am the first to provide a shoe form of one piece of metal having the upper arched portion to bear upon the upper of the shoe, and having a sole portion to bear upon practically the entire sole 30 of the shoe, so that the upper and the sole will be reshaped throughout their extent.

The invention consists in the features hereinafter described and particularly pointed 35 ed out in the claims.

In the accompanying drawings,—Figure 1 is a side elevation of my improved shoe form; Fig. 2 is a plan view; Fig. 3 is a bottom plan view; Fig. 4 is a detail view of a modification.

40 As will be seen from an inspection of these drawings, the general form of the tree or stretcher is substantially that of the interior of an ordinary shape of shoe, it having the upper arched portion 1 to bear upon the upper 45 per of the shoe, and the sole portion 2. The main body or upper portion of the form is provided with inwardly extending portions 3 at the rear, these portions being connected together in any suitable way, as by a rivet 4. 50 These portions form the lower or rear arched part of the tree, and they are slightly inclined to conform substantially to the arched portion of the sole. The sole portion of my improved shoe form is provided by extensions 5 which reach from each edge of the sole

portion inwardly to the center, being separated slightly at the center by the crevice 6. These sole portions extend practically over the entire sole of the form, and they are made up of integral extensions of the main body of 60 the metal composing the form. They are rounded at their rear ends, and are separated from the rear arched portion by a crescent-shaped opening 7. At the front or toe portion an opening 8 is provided so as to form an 65 outlet or space for the metal in the process of shaping the sheet metal of which the form is composed. Without this opening at the toe the sheet metal would crimp or buckle up at this point during the shaping operation, and 70 the same is true at the point where the crescent shaped opening is formed should it be attempted to provide a sole portion integral with the body portion without forming an opening at this point. 75

As shown in Fig. 4, the front outlet opening, instead of being formed as above described, the shoe form may be so constructed as to have this opening extend partly into the upper portion and partly into the sole 80 portion, it being located at the extreme point of the toe.

In order to force the form into its place and hold it to the desired position, I provide a lever arrangement connected with the rear portion of the form and having a heel piece 8' secured to its rear end adapted to bear upon the counter of the shoe. This lever device comprises a member 9 pivotally secured to ears 10 connected with a cross bar 11 extending 85 across the rear portion of the form and within the same, its end being riveted at 12 to the side of the form. This lever member fits between the ears, and it is provided with a series of openings 14 which join each other 90 making, in effect, a slot having rounded serrations. These openings or serrations are adapted to be engaged by a spring holding pin 15 having an enlarged portion passing through one of the ears and into the 95 desired opening 14 of the lever, and having a reduced portion or stem 16 passing through the other ear terminating in a head 17 between which and the side of the ear a spring 18 is interposed. By this construction it is 100 simply necessary to press the spring pin laterally so as to withdraw the large portion thereof from the opening 14, and then by slipping the lever member along over the pin 105 to the desired point, the spring pin, when 110

released, will engage another one of the openings 14 and hold the lever pivotally to the form. The lever or arm 9 is pivotally connected at its rear portion to a second arm 19.

5 Different degrees of stretching effect may be secured for different sizes of shoes by adjusting the toggle arm 9 in relation to the point of connection thereof with the form by the means described above, consisting of the 10 spring pin 15 and the serrated slot 14. The lever member 9 has a finger piece 9^x by which the levers may be forced down and thus put under strain in forcing the form into the shoe. This finger piece overlies the upper edge of the 15 lever member 19, but is high enough to allow the levers to be forced down slightly below the plane in which they coincide with each other, the finger piece then acting as a stop and the parts thus being locked together 20 under the strain to which they are subjected. The toe portion has a hole in the upper at 10 to facilitate its proper holding in the dies. In order to secure the stretching effect the lever arms 9 and 19 are pressed down to 25 strain the parts, the heel portion 8' being thus seated against the counter of the shoe while the toe portion is forced forward hard into place.

In order that the appliance may be packed 30 within a comparatively small compass, I may extend the slot in the lever or arm 9, as at 9", this portion of the slot however being plain, and by pressing the spring pin 15 aside the arm 9 may be slid forward within the toe 35 portion to the required extent to materially reduce the length of the apparatus. The extended slot in the lever 9 is of a width equal to the smallest diameter of the spring pin.

I claim as my invention:—

40 1. A shoe form comprising a sheet metal body portion having integral sole portions

with an opening at the toe between the body portion and the sole portions, substantially as described.

2. A shoe form comprising a sheet metal 45 body portion having the two sole portions integral therewith extending over substantially the whole sole and separated from each other by a longitudinal crevice leaving the adjacent edges free, said sole portions 50 being separated from the body portion at the toe by an opening extending from the edge of the sole portions to the edge of the body portion, substantially as described.

3. A shoe form consisting of a sheet metal 55 body portion having a sole portion integral therewith, and separated at the toe therefrom by an opening, said body portion having a lower arched portion, the said sole portion being separated by an opening from the 60 lower arched portion, substantially as described.

4. A shoe form consisting of a sheet metal body portion having the two sole portions and having extensions united together and 65 forming a lower arched portion, the sole portions being separated from each other longitudinally and separated both from the body portion at the toe and from the lower arched portion, substantially as described. 70

5. A shoe form comprising a sheet metal body portion of one piece having integral sole portions with an opening at the toe extending partly into the sole portion and partly into the upper portion, substantially 75 as described.

In testimony whereof I, affix my signature in presence of two witnesses.

MILTON B. REACH.
